UNITED STATES PATENT OFFICE

JACOB L. KLEINMAN, OF NEW YORK, N. Y.

TENNIS RACKET

Application filed November 5, 1928. Serial No. 317,198.

This invention relates generally to tennis rackets. In the ordinary tennis racket there is no means for adjusting the tension on the strings comprising the playing field of the racket with the result that the strings are always under a strain. Again in the ordinary racket, the mounting of the string on the frame is such that openings are needed along the entire periphery of the frame from the top to the neck portion thereof thereby weakening said frame at the neck portion. Furthermore, in the ordinary racket, when the ball strikes on one side of the center of the playing field in a hard manner, it is likely to turn the racket in the hands of the user. It is a primary object of the present invention to permit adjustment of the strings comprising the playing field. Another object is to prevent turning of the racket in the hands of the user. A still further object is to strengthen the racket at the point where the frame and handle meet. A more specific object is to permit ready access to the string for the purpose of mounting the same.

Other objects and advantages of the invention will appear from the description to follow taken in connection with the accompanying drawing in which—

Figure 1 is a front view of the improved racket.

Figure 2 is a cross sectional view of a modified form of handle for the racket.

Figure 3 is an enlarged fragmentary vertical sectional view of the end portion of the handle.

The improved racket illustrated in the drawing comprises a frame 10 and handle therefor, indicated generally at 11, which handle is provided with a hollow central opening 12, square shaped in cross section. The playing field within the frame consists of longitudinal and transverse strings 13 and 14, respectively, formed of gut or silk or any other suitable material. An important feature of this invention is means for adjusting the tension of these strings 13 and 14. This means includes a fan-shaped or bridge bearing member 15 provided with an elongated shank 16, square shaped in cross section but

the square shaped opening 12 in the handle 11. This shank 16 is disposed in said opening 12 and is adapted to move axially of the handle, and is provided with a reduced portion 17 at its lowermost end. Mounted on said reduced portion 17 is a metal sleeve 18 which is provided with exterior left handed screw threads 19. The sleeve is prevented from turning relative to the reduced portion 17 by means of a pin 20 passing through said sleeve and reduced portion. A washer 21 having a central opening 22 is screwed to the lowermost edge of the handle 11 and when in operative position as is shown in Figure 3, the sleeve 18 passes freely through the opening 22 of said washer. The washer 21 is embedded in a cut out portion of the handle and is substantially flush with the lower edge of said handle when so positioned as appears from Figure 3.

Adapted to be mounted on the end of the handle 11 is an extension or member 23, the outer contour of which is similar in shape to that of said handle 11 and the interior of which is formed with a central opening 24 of the same shape as the opening 12 and adapted to align therewith when said member is mounted on the handle as will be noted from Figure 3. A tube 25 having internal right handed screw threads 26 and a flange portion 27 is positioned within the opening 24, the flange portion 27 being embedded in a cut-out portion in the top edge of the member 23 to position the same substantially flush with said top edge. A pin 28 passing through the member 23 and tube 25 prevents the latter from turning relative to said member. The lower end of the extension member is finished off by means of a leather portion or cap 29 which is glued or otherwise secured thereto thereby providing a soft and convenient gripping means for the hand while operating the extension member and also to prevent the racket from slipping out of the hand of the player during the game.

With particular reference to Figure 1, it will be noted that the lower ends of the four centrally disposed longitudinal strings 13 pass through longitudinal openings 30 formed in the bearing member 15 and that the

string 13 on either side of said four central strings pass around the periphery of the shoulder 31 on each side of said member 15, all six strings then passing through a transverse opening 32 formed in the upper part of the shank 14. It will be noted that owing to the shape of the member 15 and its position relative to the frame 10, an opening 33 is provided between said parts permitting the air 10 to pass therethrough when swinging the racket and also permitting ready access to the strings for adjusting, repairing or any other purpose desired.

Another important feature of the present invention is embodied in the handle 11. This handle 11 terminates at its upper end in wings or shoulders 34, said shoulders adapted to overlie the lower edge of the frame 10 thereby reinforcing the frame at this point. Between the shoulders 34 the handle is provided with a dished out portion indicated at 35 thereby enlarging the said opening 33. At its lower end at a point about where the handle is gripped by the user, one side thereof 25 is formed with corrugations 36 to permit the fingers or other part of the hand to obtain a grip. In the modified form of handle shown in Figure 2, corrugations 37 are formed thereon entirely around its periphery and not only 30 on one side thereof as in the handle in Figure 1.

In using the improved racket, if it is desired to tighten the strings 13 and 14, the extension member 23 is turned to the right, 35 which turning by reason of the engagement of the sleeve 18 and tube 25 draws the shank 16 with the bearing member 15 downwardly with a consequent pull on the six strings carried by the member 15. By reason of the 40 mounting of said six strings on the member 15 this is a straight downward pull and results in a tightening of all of the strings comprising the playing field. The downward movement of the member 15 is limited by 45 reason of the shoulders 31 engaging the frame 10. While only six strings are shown carried by the member 15 thereby placing the lowermost opening in the periphery of the frame at the point indicated at 39, it will be 50 understood that the number of strings carried thereby will depend upon the size of said member and the more strings carried by said member the higher the point on the frame at which the lowermost opening will appear. 55 A turn of the member 23 to the left will permit the strings to loosen and the member 15 to return to the position indicated by the dot and dash line 38 the hollow central opening 12 of the handle 11 and shank 16 of member 15 being of square shape in cross section will prevent side movements or turning of shank 16 in opening 12 during operation, thereby preventing the twisting of the strings, but will only permit the up or down 60 movements of such shank in said opening, 65

thereby pulling the strings straight down when tightening and tensioning same by operating extension 23.

It will be understood that the corrugations formed on the handle 11 afford means for firmly gripping the handle to prevent the same from turning in the hand.

In reduction to practice I have found that the form of my invention illustrated in the drawing and referred to in the above description is the most efficient and practical, yet I desire to emphasize the fact that various minor changes in the details of construction, proportions and arrangement of parts may be resorted to when required without sacrificing any of the advantages of my invention as defined in the appended claims.

I claim:

1. In a racket, a frame having strings mounted therein, a handle, said handle being formed with a central longitudinal opening, a shank disposed in said opening, said central opening and said shank being square shaped in cross section, said shank being connected to one or more of said strings, and means for adjusting the shank longitudinally in said opening to vary the tension of such strings.

2. In a racket, a frame, a handle having an opening, a bridge portion forming a string tensioning device mounted in said frame, a shank extending from said bridge portion into said opening and operatively connected to an extension member forming a part of said handle, said bridge portion and said shank provided with openings to receive a string.

3. In a racket, a frame, a handle having an opening, a bridge portion forming a string tensioning device mounted in said frame, a shank extending from said bridge portion into said opening and operatively connected to an extension member forming a part of said handle, said shank provided with an opening to receive strings and said bridge portion provided with openings to keep said strings apart from each other.

4. A tennis racket comprising a frame, a handle therefor, a plurality of strings mounted within said frame, an anchoring member for one or more of said strings movable to vary the tension of such strings; said anchoring member provided with a plurality of openings for receiving said strings in spaced relation, and movable means providing an extension of the handle surface and in screw threaded connection with said anchoring member to adjust the latter longitudinally of said frame.

5. A tennis racket comprising a frame, a hollow handle, a plurality of strings mounted within said frame, an anchoring member connected to certain of said strings and movable longitudinally of said frame to vary the tension of such strings and comprising a

rigid shank disposed in the hollow of said handle and movable axially thereof, and movable means providing an extension of the handle surface and in screw threaded engagement with said shank for moving the same.

6. A tennis racket comprising a frame, a hollow handle therefor, a plurality of strings mounted within said frame, an anchoring member for certain of said strings comprising a shank disposed in and movable axially in the hollow of said handle, and means for moving said shank comprising a rotatable element forming part of the handle and providing an extension of the handle surface, an externally screw threaded sleeve mounted on the end of said shank, an internally screw threaded tube carried by said rotatable element and adapted to engage said sleeve.

20 7. In a racket, a frame having a throat portion, strings positioned within said frame, a handle, a bridge member anchoring certain of said strings and positioned in said throat portion, a shank attached to said bridge member, an extension member forming a part of said handle and providing an extension of the handle surface and in screw threaded engagement with the bottom end of said shank.

8. In a racket, a frame having a plurality 30 of strings mounted therein, a hollow handle, a shank connected with one or more of said strings and movable to vary the tension thereof, said shank and the bore of said handle being of angular cross-section throughout at least a portion of their length, whereby angular movement of the shank is prevented, and means for moving said shank longitudinally.

9. In a racket, a frame having a plurality 40 of strings mounted therein, a hollow handle, a shank connected with one or more of said strings and movable to vary the tension thereof, said shank and the bore of said handle being of non-circular cross-section throughout at least a portion of their length, and means for moving said shank longitudinally.

45 10. In a racket, a frame having a plurality of strings mounted therein, a hollow handle, a shank positioned in said handle and connected to one or more of said strings, means in screw threaded engagement with said shank for moving the latter longitudinally, said means forming a part of the handle and providing a portion of the outer surface thereof, said shank and the bore of said handle being angular in cross-section throughout at least a portion thereof, and 55 said shank fitting snugly within such portion of the handle and being thereby restrained against lateral movement.

11. In a racket, a frame having strings 60 mounted therein, a hollow handle, a shank in said handle, said shank being connected at

one end to one or more strings and connected to an extension member at its other end, said member forming a part of said handle and operable to adjust said shank longitudinally, the shank and the bore of said handle being 70 of like non-circular cross-section so as to permit the up and down movement of said shank in the bore of the handle and fitting snugly in said bore to prevent lateral movement of said shank in said bore upon operation of 75 the extension member.

12. In a racket, a frame having strings mounted therein, a handle having a longitudinal square opening formed therein, a string tensioning device having a square shank and mounted in said frame, said shank disposed in said opening, and an extension member forming a part of said handle and providing a portion of the surface thereof and operatively connected to said shank to move the 80 same longitudinally.

13. In a racket, a frame, a handle having an opening, a bridge portion forming a string tensioning device mounted in said frame, said bridge portion having a shank extending into said opening, and means for moving said shank longitudinally, said shank having a transverse opening for receiving one or more strings, and said bridge portion being provided with longitudinal openings for receiving the strings and holding the same in spaced 95 relation.

14. A tennis racket comprising a frame, a handle therefor, a plurality of strings mounted within said frame, an anchoring member for one or more of said strings movable to vary the tension of such strings, movable means providing an extension of the handle surface and connected to said anchoring member to adjust the latter longitudinally of said frame, said means comprising a tubular member, and a cap providing a friction gripping surface closing the end of said tubular member and covering at least a portion of the outer surface of such member.

15. A tennis racket comprising a frame, a hollow handle therefor, a plurality of strings mounted within said frame, an anchoring member for one or more of said strings movable within said handle to vary the tension of such strings, rotatable means providing an extension of the handle surface and connected to said anchoring member by a screw threaded tubular element to adjust the anchoring member longitudinally of said frame, and a spacing element arranged between the opposing ends of the handle and rotatable means to maintain such ends in spaced relation.

16. The combination as set forth in claim 125 6 wherein said tube is made of metal and includes an annular flange positioned between the opposing ends of said handle and rotatable element to maintain such ends in spaced relation.

17. A racket comprising a frame, a hollow handle therefor, strings mounted within said frame, an anchoring member for one or more of said strings movable within said handle to vary the tension of such strings, a movable member providing an extension of the handle surface, said movable member formed with an opening, means arranged within said opening at one end of said movable member to engage one end of said anchoring member to adjust the latter longitudinally of said frame, and a cap providing a friction gripping surface covering the other end and also at least a portion of the outer surface of such movable member.

In witness whereof, I hereunto affix my signature.

JACOB L. KLEINMAN.
